(57) **CLAIM**

The ornamental design for a digital camera, as shown and described.

DESCRIPTION

FIG. 1 is a bottom, front and right side perspective view of a digital camera showing the new design;

FIG. 2 is a top, rear and left side perspective view thereof;
FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of portion 9 shown in FIG. 1. The broken lines depict portions of the digital camera that form no part of the claimed design. The dot-dash broken lines encircling an enlargement portion of the design forms no part of the claimed design.
